UNITED STATES PATENT OFFICE.

NATHAN S. JOHNSON, OF PORTLAND, OREGON.

WASHING-MACHINE.

SPECIFICATION forming part of Letters Patent No. 377,829, dated February 14, 1888.

Application filed May 23, 1887. Serial No. 239,114. (No model.)

To all whom it may concern:

Be it known that I, NATHAN S. JOHNSON, a citizen of the United States, residing at Portland, in the county of Multnomah, State of Oregon, have invented certain new and useful Improvements in Washing-Machines, of which the following is a specification, reference being had therein to the accompanying drawings.

This invention relates to improvements in boiler washing-machines; and the nature of the invention consists in combining with a boiler a cylinder rotating within the same provided with transverse interior troughs or buckets having acute angular ribs, and the recess between said ribs parallel with the periphery of the cylinder, and said portion provided with a series of perforations opposite slots in said cylinder, and in the walls of the cylinder perforations protected by shields extending within said cylinder.

It consists, also, in combining with the cylinder a boiler and its cover made substantially steam-tight by means of fibrous packing placed and retained between their edges, as will be hereinafter described in connection with the drawings, in which—

Figure 1 is a perspective view of a machine constructed in accordance with my invention, showing the cover removed and lying alongside thereof. Fig. 2 is a transverse vertical section of the same. Fig. 3 is a longitudinal vertical section of the same. Fig. 4 is a perspective view of one of the troughs of the cylinder removed therefrom.

In said drawings, A represents a boiler adapted to be placed upon a stove to have its contents heated. The cover of the boiler is represented at B, its bottom edge grooved at b to receive the re-enforced upper edge, a, of the boiler, and within the grooves b is placed a packing, b², preferably of fibrous material, to form a substantially steam-tight joint between the boiler and its cover, the two being retained 45 united by the bails b³, hinged to the cover, having the lower ends in engagement with pins a³, projecting from the ends of the boiler.

The cylinder D is formed of a large section, forming the body of said cylinder, and a small 50 segmental section, forming the cover thereof, said sections being hinged together on one side at d and retained united on the opposite

side by means of a spring-catch, d², and lug d³. The cylinder is provided with trunnions d⁴ d⁵, and the latter is adapted to receive a handle, d⁶, to rotate it, said trunnions resting in bearings. To produce a certain amount of rubbing action upon clothing and permit the passage of water and steam into the cylinder, the latter has a series of horizontal slots, D², in its periphery, and opposite said slots there are secured against the interior of said periphery a series of troughs or buckets, E, of peculiar form. They are substantially in the form of letter VV, with the valley between the two V- 65 ribs much larger than heretofore, and perforated at e for the passage of steam and water received directly through the slots D². The ribbed sides of the buckets have also perforations e², for the escape of water therefrom while 70 performing the upper half of their revolution, and thus sprinkling the clothing with suds.

The perforation e² being distant from the edge of the acute angles of the ribs, the latter prevent the perforations e², as well as the perforation e, from becoming obstructed by the clothing.

To prevent the openings e in the sides of the cylinder becoming obstructed also by the clothing in said cylinder, shields C are secured to the inner surface thereof opposite said openings, but at some distance therefrom. Soap and water or other saponaceous compound is introduced in the boiler and the latter placed upon a stove. The clothing to 85 be washed is placed in the cylinder and rotation imparted thereto. The clothing during the operation is turned over and over, the upper surface being subjected to the purifying effect of the steam entering the cylinder 90 through the orifice above the point of submergence of the cylinder, and this, in connection with the soapy water, rapidly removes the impurities of the clothing.

I am aware that the cylinder of boiler washing-machines has been provided with troughs or buckets of various forms; but I am not aware that said buckets have been provided with a series of perforations in the valley between two angular ribs, and said perforations 95 thereby protected against clogging.

I am also aware that unshielded perforations have been made in the walls of the cylinder, and do not claim them, broadly.

I am also aware that packing has been used between a wash-boiler and its cover.

Having now fully described my invention, I claim—

- 5 1. In a washing-machine, the combination of a boiler, a cylinder therein having transverse slots in its periphery, with interior troughs having two ribs provided with perforations in the valley between said ribs, the latter perforations being opposite the slots in the cylinder, substantially as and for the purpose described.
- 10 2. In a washing-machine, the combination

of a boiler, a cylinder therein having transverse slots in its periphery, and perforated 15 troughs opposite said slots, said boiler having also perforations *c* in its side walls and imperforated plate-shields *C* opposite said perforations and standing parallel with said walls, substantially as and for the purpose described. 20

In testimony whereof I affix my signature in presence of two witnesses.

NATHAN S. JOHNSON.
